UNITED STATES PATENT OFFICE.

GEORGE L. CORCORAN AND GEORGE A. DOBYNE, OF ST. LOUIS, MISSOURI, ASSIGNEES
TO CHAMPION SHOE MACHINERY COMPANY, OF ST. LOUIS, MISSOURI, A CORPOR-
ATION OF MISSOURI.

SHOE-SEWING MACHINE.

1,056,750.

Specification of Letters Patent. Patented Mar. 18, 1913.

Application filed July 21, 1911. Serial No. 639,835.

To all whom it may concern:

Be it known that we, GEORGE L. CORCORAN and GEORGE A. DOBYNE, citizens of the United States, and residing at St. Louis, in the State of Missouri, have invented certain new and useful Improvements in Shoe-Sewing Machines, of which the following is a specification.

This invention relates to shoe sole sewing machines and particularly to that type known as inseam sewing machines, *i. e.*, machines for sewing the inseam of a welt or a turned shoe.

This invention is an improvement on the machine forming the subject matter of Patent No. 412,704, granted Oct. 8, 1889 to French and Meyer.

The objects of this invention are to improve the machine of the above patent so as to simplify its construction and the arrangement of its parts and actuating mechanisms, so that the machine will be capable of being run at high speed.

The invention will be described in connection with the accompanying drawings in which:

Figure 1 is a side elevation of the machine embodying this invention, a part of one of the brackets forming the frame or head being cut away to show the cam and links, Fig. 2 is a front elevation, Fig. 3 is a detail side elevation showing the awl and its actuating mechanism, and Fig. 4 is a section on the line 4-4 Fig. 3.

In the drawings those parts corresponding to like parts in said patent have been designated by the same reference characters as in said patent to which patent reference is had for details of construction. The frame or head A, the drive shaft A', the cam wheels A⁴ and A⁵, the awl carriage B operated from the cam wheel A⁵ through the lever A⁶ and having a depending portion B' for supporting the channel guide lever a² and its channel guide a', the needle a⁶, the thread looper B² and its lever B^x operated from the cam wheel C', the sliding gage B⁵ and its locking mechanism, the welt guide a⁵ its sliding bar N³ and its locking means, are all constructed and arranged as in said patent and need not therefore be described in detail. The thread-finger d is constructed as in said patent, but is operated by different mechanism. The arm D⁵ upon the thread-finger rock shaft D⁶ has

pivots connected thereto one end of a link or bar 10 which is provided at its other end with a slotted head 11 having a sliding bearing upon the drive shaft A'. This link has mounted thereon a cam roll 12 engaging a cam groove 13 on the left hand face of the cam wheel D'. This cam groove is arranged to operate the thread-finger in the same timed relation with respect to the other mechanism as in said patent. 60

The take-up lever b² and the auxiliary take-up b⁵ are constructed and operate as in said patent, but are actuated by different mechanism. The arm C³ on the take-up rock shaft C⁵ is pivotally connected to one end of a link or bar 15, the other end of which is provided with a slotted head 16 having a sliding bearing on the drive shaft A'. The link 15 has mounted thereon a cam roll 17 engaging a cam groove 18 in the left hand face of the cam wheel D'. The cam groove 18 is so constructed as to operate the take-up in the same timed relation with respect to the other mechanism as in said patent. The awl a and its lever A³ are 80 constructed and operate as in said patent, but are actuated by different mechanism. The awl lever is mounted upon the carriage B to oscillate toward and from the work, and is arranged to move with the carriage 85 to feed the work. The arm 20 is slotted or forked to receive a block 21 pivotally mounted upon one end of a link 22, the other end of which is provided with a slotted head 23 having a sliding bearing upon the drive shaft A'. The link is provided with a cam roll 24 engaging a cam groove 25 on the right hand face of the cam wheel C'. In order to more firmly support the link 22 against sidewise movement, a guide 26 is 90 provided which is secured to the head A and supports and guides the link in its movements. The cam groove 25 is constructed to operate the awl in the same timed relation with respect to the other mechanism as 95 in said patent. The awl and its carrying lever A³ move with the carriage B during the feeding movements, but the sliding connection between the arm 20 and the block 21 permits of this movement, while the link 22 will be supported and guided by its guide 26.

The movement is transmitted direct to the operated parts, due to the fact that there is practically a direct connection between the arms D⁵, C³ and 20 and their actuating cams. 110

A plurality of connecting levers and links are therefore dispensed with, and the application of the forces by the actuator members to the actuated members is direct. The 5 links 10, 15 and 20 may be of light construction, in view of the fact that they can be made of comparatively thin steel bars. The inertia of these moving links is therefore small, first due to their light weight, 10 second due to their relatively small movement, and third due to the fact that they move in the direction of their length. The machine can therefore be run at very much higher speed than machines in which the 15 connections are made through swinging members or levers, since the vibration will be less, keeping in mind that vibration is the factor which determines the speed of a machine. The construction is also simpler 20 as in prior machines. Thus it will be noted that the height of the machine has been reduced and the head itself has been reduced down to the level of the drive-shaft A' so that the cams are always in full view which 25 is desirable. The links are supported against lateral movement in a simple manner. The links 10 and 15 are supported laterally between the cam face of the cam wheel D', and the hub H of the left pedestal 30 on the frame A.

It is obvious that various changes may be made in the details of construction without departing from this invention, and it is therefore to be understood that this invention is not to be limited to the specific construction shown and described.

Having thus described the invention what is claimed is:

1. In a shoe sole sewing machine, the combination of a machine head, a driving shaft

thereon, a cam wheel on said shaft having a plurality of cam grooves in one side thereof, a plurality of thread engaging members, rock shafts for supporting said members and mounted on said head, arms mounted 45 on said rock shafts and positioned on one side of said head, links connected at one of their ends with said arms, said links having at their other ends sliding bearings extending across said driving shaft and positioned on one side of said cam wheel, and cam rolls on said links engaging said cam grooves.

2. In a shoe sole sewing machine, the combination of a machine head, a driving shaft 55 on said head, a cam on said shaft, a pivotally mounted awl having a slotted arm, a link having a block engaging said slotted arm, guides on said head for supporting said link for sliding movement thereon, and a 60 cam roll on said link engaging said cam.

3. In a shoe sole sewing machine, the combination of a machine head, a driving shaft on said head, a cam on said shaft, a pivotally mounted awl, a laterally movable carriage for said awl, a guide on said head, a link mounted on said head to slide in said guide and having a cam roll thereon engaging said cam, and means for slidingly connecting said link with said awl to actuate 70 the same and permit lateral movement of said awl.

In testimony whereof we affix our signatures in presence of two witnesses.

GEORGE L. CORCORAN.
GEORGE A. DOBYNE.
